FISHING ROD HOLDER OR THE LIKE

Leslie J. Poglein, Jeannette, Pa.

Application May 14, 1958, Serial No. 50,884

Term of patent 14 years

(Cl. D31—4)

Fig. 1

Figure 1 is a perspective view taken from a side of a fishing rod holder or the like, showing my new design; and

I claim:

The ornamental design for a fishing rod holder or the like, as shown.
